BY *H. G. Manning*

ATTORNEY

34 into the inner and outer wick channels 31 and 30.

The oil chamber cover 47 is provided with radially disposed arms 48, 49, 50, and 51 (see Figs. 1 and 3) adapted to seat themselves against the radially disposed seats 60 (Fig. 4) rabbetted or otherwise formed in the upper edges of the walls of the radially disposed ducts 61, 62, 63, and 64 to seal the vaporized oil in said ducts.

A perforated cup-shaped cover 53 is removably seated upon the central sleeve 52. Similarly, a pair of concentric cover ring plates 58 and 59 enclose the upper ends of the passageways 34 and 33, respectively. The sleeves 54 and 56 are preferably offset inwardly at their upper ends to provide annular seats for the ring plates 58 and 59 (see Fig. 4).

Each burner base 29 and its associated series of covers 47, 53, 58, and 59, and its perforated sleeves 52, 54, 55, 56, and 57 constitute a distinct unit, which is adapted to be detachably supported by the burner base support 18.

Each fountain 26 is provided with a pair of laterally projecting channelled ears 27 and 28 (Fig. 4), which with the hollow stem of the fountain conform substantially to the shape of the letter T. The ears 27 and 28 comprise an upper cross bar which is adapted to enter the elongated rectangular opening 35, formed in the hub of the burner base 29 when said base is rotated until the cross bar of the T-shaped fountain 26 registers with said rectangular opening. In order to prevent oil flowing through the fountain 26 and into the burner from leaking out through the rectangular opening 35, said opening is provided with an upwardly projecting peripheral rim 70.

Each fountain 26 is mounted upon one arm of the H-shaped burner base support 18 in any suitable manner, as by a male threaded stem threadably engaged in one of the tapped holes located substantially at each intersection formed by one of the arms with one end of the cross bar of the H-shaped burner base 18.

An oil supply pipe 25 of larger diameter may likewise be threadably secured in the arm of the burner base 18 at the bottom thereof.

In order to exclude air from the chamber 32, provision is made of an apertured square plate 24 having an opening therein only large enough to accommodate the stem of the fountain 26, and a coiled spring 23 carried by the stem of the fountain is seated between the apertured plate 24 and the top of the H-shaped burner base.

The ducts under the ears 27 and 28 deflect the oil supplied through the oil supply pipe 25 outwardly against the walls of the central oil chamber 32 in its passage to the outer and inner wicks 42 to 45, inclusive.

The apertured plate 24 is so proportioned that when seated against the bottom wall of the rectangular opening 35 by the coiled spring 23, the central oil chamber 32 is completely sealed off with an air tight seal, so that no air can enter the oil chamber 32 from below.

The lugs 19, 20 are drilled and threaded to receive the machine screws 39, 40, respectively.

Each burner base 29 is provided with arms 36 and 37, which are fashioned in the form of ears, adapted to engage and disengage the lugs 19 and 20, respectively, when the burner base 29 is rotated upon the apertured plate 24 relative to its associated fountain 26. The machine screws 39, 40 when screwed tight, lock the arms 36, 37

upon their associated lugs 19, 20 to secure the burner unit against rotation relative to the burner base support 18.

The perforated shells 52, and 54 to 57 are preferably made of heavy heat-resisting steel, and may be coated with porcelain to facilitate cleaning. The covers 47 and 53, and the ring plates 58 and 59 may also be coated in the same way.

The oil fountain 26 is spaced above the floor of the central oil chamber 32 to reduce the risk that any carbon may clog the fountain and prevent it from functioning correctly.

The cover 47 can be readily removed to afford access to the radially disposed channels 61 to 64 for cleaning purposes, to insure that the oil may flow properly.

When the burner base unit 29 is attached to the fountain 26 in operative position, and the oil chamber 32 is closed by the cover 47, the apertured plate 24 and cover member 47 seal off air from the central oil chamber 32.

Operation

In assembling the apparatus, the pedestal 10 will first be anchored, and the squared shaft 17 of the burner base support 18 then inserted in the squared shell 11, after which the base support 18 is adjusted to the desired level. The adjusting screws 12 to 15 are then tightened to lock the base support 18 to the pedestal 10. The supply pipe 25 is then installed.

The stem of the fountain 26 is now passed through the apertured plate 24 and the coiled spring 23, and said stem is then screwed into the base support 18.

The burner base 29 is now placed above the fountain 26 with the elongated opening 35 registering with the channelled ears 27 and 28 of the fountain. The burner base 29 is next pushed downwardly, sliding the apertured plate along the stem of the fountain 26 against the increasing tension of the coiled spring 23, until the channelled ears 27, 28 clear the ridges of the walls of the elongated opening 35. The burner base 29 may then be twisted about the stem of the fountain 26 until the channelled ears 27, 28 are disposed transversely to the elongated slot 35.

The coiled spring 23 will then lift the apertured plate 24 and the burner base 29 until the ridges of the walls of the opening 35 engage beneath the channelled ears to lock the burner base 29 in operating position. In this position, the burner base arms 36, 37 will engage their associated lugs 19, 20, and the machine screws 39, 40 will then be screwed tight. The cover 47 is next set in place, followed by the setting of the central sleeve 52 and its cover 53, and the sleeves 54 to 57, and the ring plates 58 and 59.

It will be understood that the burner base 29 and its associated sleeves and covers may be removed as one unit, whenever desired. This is accomplished by releasing the screws 39, 40, forcing the burner base 29 and apertured plate 24 downwards against the tension of coiled spring 23 until the channelled ears 27, 28 clear the ridges of the walls of the elongated slot 35; rotating the burner base 29 until the fountain 26 registers with the slot 35; and then lifting the burner base unit until it clears the fountain 26.

One advantage of the present invention is that the installation and removal of the burner base unit may be accomplished without removing any of the oil line fittings on the fountain 26.

While there has been disclosed in this specifi-

tion one form in which the invention may be embodied, it is to be understood that this form is shown for the purpose of illustration only, and that the invention is not limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an oil burner, a base support, an upwardly-extending oil fountain fixed upon said base support, a burner unit detachably secured to said base support comprising a burner plate having a plurality of annular spaced partition walls extending upwardly therefrom, said partition walls constituting a wick channel and enclosing a central chamber, a duct interconnecting said chamber and said wick channel, a cover closure for said central chamber and said duct, a perforated shell detachably supported by the outer wall of the wick channel, said burner plate having an opening in the bottom of the central chamber, said fountain projecting loosely through said opening into said central chamber, and means to prevent the escape of oil through said opening.

2. In an oil burner, a base support, an oil fountain secured to and extending above said base support, a burner unit comprising a burner plate having a plurality of annular partition walls concentrically arranged in spaced relation, said walls in conjunction defining a wick channel surrounding a central chamber, a radial duct interconnecting said central chamber and said wick channel, said burner plate having an elongated opening in the bottom of the central chamber, said base support detachably carrying said burner plate with said opening loosely receiving said oil fountain, and means for locking

said burner unit to said base support to hold said oil fountain within said central chamber.

3. In an oil burner, a base support, a burner unit comprising a burner plate having an oil chamber, means for detachably supporting said burner unit on said base support, said oil chamber having an elongated opening in the bottom thereof, and a T-shaped oil fountain secured to said base support and projecting upwardly through said elongated opening, said fountain overhanging the sides of said opening, and adapted to pass through said opening when the fountain is turned to align vertically with the opening, whereby the burner unit may be readily applied to and removed from the base support without disturbing any oil supply connection of the burner.

4. The invention as defined in claim 3, in which said elongated opening is provided with an upstanding rim, the upper portion of said oil fountain comprising downwardly inclined channelled ears overhanging said rim, whereby oil dropping from said ears will be prevented from escaping downwardly through said opening.

5. The invention as defined in claim 3, wherein said oil fountain is provided with a closely fitting slidable apertured plate covering said elongated aperture, and a spring urging said apertured plate against the lower surface of said burner plate, whereby the passage of air through said elongated aperture will be prevented.

JOSEPH F. COSCIA.
